UNITED STATES PATENT OFFICE.

EDGAR L. MADDOX, OF TULSA, OKLAHOMA.

OIL-TANK.

1,165,011.

Specification of Letters Patent. Patented Dec. 21, 1915.

Application filed September 19, 1914. Serial No. 862,586.

To all whom it may concern:

Be it known that I, EDGAR L. MADDOX, a citizen of the United States, residing at Tulsa, in the county of Tulsa and State of Oklahoma, have invented certain new and useful Improvements in Oil-Tanks, of which the following is a specification.

My invention relates to improvements in oil tanks.

It is customary to construct oil tanks with an opening in or near the top thereof, to permit of the escape of gases from the oil. These gases are readily combustible and escaping from the tank ascend in the air, forming a gas column of considerable height, which leads directly to or is connected with the tank and its contents. It not infrequently happens that during a thunder storm, the lightning strikes this column of gas which is accordingly ignited, the flame of the same descending and igniting the oil within the tank. Tanks thus constructed, due to the lack of proper means to release excessive pressure upon the ignition of the contents, not infrequently burst whereby all of the oil or the like is destroyed, if not greater damage done. Attempts have heretofore been made to provide means to extinguish the burning oil within tanks after the same has been ignited as above indicated, but the same have not proven wholly satisfactory, due principally to the fact that they are expensive to manufacture, do not properly relieve the excessive pressure in the tanks whereby explosions are liable to occur and require the attention of attendant or attendants.

An important object of the invention is to provide means which will permit of the proper escape of gases from the oil within the tank whereby explosions are prevented, and upon the contents of the tank being ignited by the lightning or the like, will relieve the excessive pressure within the tank, and quickly extinguish the fire by smothering the flame or cutting off the supply of air to the burning oil.

A further object of the invention is to provide a tank of the above mentioned character, so constructed that rain cannot enter the same and become mixed with the oil.

A further object of the invention is to provide a tank of the above mentioned character, which is simple in construction, inexpensive to manufacture, strong and durable.

Other objects and advantages of the invention will be apparent during the course of the following description.

In the accompanying drawing forming a part of this specification and in which like numerals are employed to designate like parts throughout the same, Figure 1 is a central vertical sectional view through a tank embodying my invention, and, Fig. 2 is a plan view of the same.

In the drawings, wherein for the purpose of illustration is shown a preferred embodiment of my invention, the numeral 5 designates a preferably cylindrical shell or casting, constituting the body portion of the tank, the lower end of which is closed by a bottom 6, connected therewith as shown at 7, to form a gas tight union. The upper end of the shell 5 carries a top or cover 8, rigidly attached thereto as shown at 9, for forming a gas tight union therewith. This top or cover is preferably annular and has a preferably central outlet opening 10, as shown. The top or cover 8 is curved in cross-section, and extends downwardly toward its edges, as shown.

Arranged within the central portion of the upper end of the shell 5 is a preferably conical or funnel shaped deflector 11, disposed near and below the opening 10, to cover the same but spaced therefrom, providing a permanent gas outlet passage 12, of suitable size. The deflector 11 is connected with a preferably vertical pipe 13, the lower end of which is preferably rigidly attached to the bottom 6. The deflector 11 is steadied by spaced radially arranged arms or rods 14, as shown.

Within the lower end of the pipe 13 is a plug 15, and a water drain pipe 16 leads into the pipe 13 above and adjacent the plug 15. The pipe 16 passes to the exterior of the shell 5, to draw the water away from the shell. The function of the plug 15 is to prevent accumulation of water in the lower end of the pipe 13.

In operation, the permanent gas discharge opening 12 permits of the proper escape of the gases from the oil contained within the shell 5. These gases escape to the atmosphere and ascend, as is well known. Should the oil within the tank become ignited, by the lightning or otherwise, the excessive pressure therein is relieved by passage thereof through the discharge opening 12. The products of combustion containing prin-

cipally carbon dioxid are entrapped within the upper end of the shell, due to the deflector 11 and the cover 8, the same forming in effect a continuous curved deflecting surface, whereby these products of combustion are deflected downwardly, inwardly and outwardly. In this manner, the greater portion of the products of combustion are retained within the upper portion of the shell, forming a blanket for smothering the flame, or excluding air from the burning oil. The deflector 11 catches the rain or water from the cover 8, the same passing out of the tank through the pipes 13 and 16.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. An oil tank of the character described, comprising a shell having a cover curved in vertical cross section and provided with a substantially centrally arranged outlet opening having its wall arranged within a horizontal plane beneath the outer edge of the

cover, a tapering deflector arranged within the shell beneath the cover and spanning the outlet opening thereof and vertically spaced from the outlet opening for a substantial distance to be arranged wholly below the outer edge of the cover, and a water drain pipe connected with the tapered deflector and extending to the exterior of the shell.

2. An oil tank of the character described, comprising a shell for holding the oil; an approximately annular cover attached to the top of the shell and having an approximately centrally arranged opening with the material of the cover near the opening inclined downwardly toward such opening; a tapering deflector arranged within the shell beneath the cover and spanning the outlet opening thereof and vertically spaced from such opening for a substantial distance to provide a permanently open passage; and a water drain pipe connected with the deflector and extending to the exterior of the shell.

In testimony whereof I affix my signature in presence of two witnesses:

EDGAR L. MADDOX.
